UNITED STATES PATENT OFFICE.

ROY BERKELEY SIMPSON, OF DALLAS, TEXAS, ASSIGNOR OF ONE-HALF TO
W. E. KAYE, OF FORT WORTH, TEXAS.

MANDOLIN.

SPECIFICATION forming part of Letters Patent No. 627,067, dated June 13, 1899.

Application filed February 4, 1898. Renewed May 19, 1899. Serial No. 717,481. (No model.)

To all whom it may concern:

Be it known that I, ROY BERKELEY SIMPSON, a citizen of the United States, residing at Dallas, Texas, have invented certain new and useful Improvements in Mandolins, of which the following is a specification.

My invention relates to mandolins; and the objects are to obtain a tone for mandolins as nearly as possible equal to that of violins and other stringed instruments played by bows, to attain a penetrating tone never before accomplished, to obtain harmonics as readily as on bow stringed instruments, to avoid the harsh metallic tones so common in mandolins, to make the mandolin more durable, and to prevent the instrument from splitting and cracking when subjected to sudden changes of temperature. I accomplish these objects by the novel construction and arrangement of parts hereinafter fully described, and more particularly pointed out in the claims.

Reference is had to the accompanying drawings, forming a part of this specification.

Figure 1 is a plan or top view of a mandolin, showing the improved sounding-board. Fig. 2 is a view of the sounding-board inverted, showing arrangement of braces, bars, and sound-holes. Fig. 3 is a side elevation of one of the braces. Fig. 4 is a side elevation of the bass bar. Fig. 5 illustrates a shield for preventing the finger from dropping in the sound-hole on the right side of the sounding-board.

Similar characters of reference are used to indicate corresponding parts throughout the several views.

The construction of the neck and the finger-board, which is provided with steel frets, is the same as shown in Letters Patent of the United States granted to me on November 30, 1897, No. 594,436. My improvements over that patent consist in the arrangement of braces about the sounding-holes, the improved bass bar, and a shield for the finger. Braces B and B' are glued to the under side of the sounding-board, and the ends of said braces are mortised in the shell and the usual reinforcing-strip of the mandolin. These braces each have a notch or groove cut therein, as shown in Fig. 3, for the bass bar A. Careful experiments have demonstrated the fact that the

bass bar A must not touch the braces. In order to get the best effect, the bass bar must have perfect freedom to vibrate with the sounding-board. The bass bar is glued to the under side of the sounding-board under the G or large strings and parallel therewith except from the bridge back to the tailpiece. The sounding-board is made thinner on the right side than on the left side, the right side being the treble and the left side being the bass side. In locating the bass bar it is necessary to locate first the nodal lines of the sounding-board and then place the bar along or near said lines. This bar is extended almost the entire length of the sounding-board in order to give more weight to the bass side of the instrument, whereby a richer violin-like tone is given to the sounding-board. Having more weight on the bass side and less weight on the treble side of the sounding-board secures an even distribution of tone-power. This is accomplished in part by placing the bass bar as above described and by making the treble side of the sounding-board thinner than the bass side before the bass bar is glued on. Bass bar A is beveled, so that it will conform to the bevel or angle in the sounding-board. The bars a and a' are also glued to the under side of the sounding-board and prevent the splitting of said board caused by the sudden changes of temperature. The bar a' must have a groove cut in the top for bar A, so that these bars will not touch each other.

85 The sound-holes g g are preferably J-shaped or S-shaped. They may have the shape of the S-mark, or they may be straight parallel holes, or they may be in the shape of ornamental or fancy scrollwork on each side of and parallel with the strings, but must be on each side of the strings. This arrangement of the sound-holes allows an extension of the finger-board, and the arrangement of the sound-holes with the bars and braces, as above described, and 90 illustrated in the drawings, gives the greatest possible range to the vibrating air capacity of the instrument. In making the bottom and top of the J's breaks are made in the slots, leaving bars connecting the parts of the board 95 inside the curves with the parts outside of the curves. The curved bars c c and h h pass

under these breaks in the slots and are glued securely to the sounding-board. By careful experiments these bars can be located along the nodal lines about the sound-holes and must necessarily be located along the nodal lines in order to get the best effect and not to deaden sound or impair it. These bars are necessary to protect the delicate parts of the sounding-board. The particular arrangement of the sound-holes and the bass bar A gives a smooth tone necessary for the rendition of slurred passages in music, as well as making it possible to tune the mandolin to a higher pitch than other mandolins. All of the bars are glued to the under side of the sounding-board and must be made of some suitable wood whose acoustic properties correspond with the acoustic properties of the wood used in constructing the mandolin.

In Fig. 5 is illustrated a shield R for preventing the finger from dropping in the sound-hole on the right side of the mandolin. The shield is attached to a holder P by screws or other suitable means. This holder P may be made of vulcanized rubber or some hard substance. It is provided with a slot by which it is attached to the bridge M. The oval part of the holder rests on the narrow portion m of the bridge. The shield is held close to the sounding-board and does not touch it.

Besides the advantages gained by the improvements herein set forth my mandolin has all the advantages set forth in my former patent, to which reference has been made.

Having fully described my invention, what I claim, and desire to secure by Letters Patent, is—

1. A mandolin having a sounding-board provided with sound-holes in each side thereof consisting of curved slots, a bass bar extending substantially the entire length of said board and glued to the under side to the left of the central part thereof, cross-braces, and two-bars arranged at an angle about the tail part of said board all glued to said board, each of said braces and one of said bars having a groove for said bass bar whereby said bass bar is adapted to vibrate with said board independently of said braces and said bar. 40

2. A mandolin having curved sound-holes arranged symmetrically in each side thereof, a bass bar glued to said board under and parallel to the G strings and extending substantially the entire length of said board, the treble side of said board being made thin 55 whereby the nodal lines thereof will be along said bar, and cross-braces glued to said board without touching said bass bar. 50

3. A sounding-board having sound-holes arranged in each side thereof and bars and cross-braces attached to the under side of said board and adapted to strengthen the delicate parts thereof, each bar or cross-brace having a notch or groove cut therein at the crossing of said bar and brace whereby said bars vibrate with said board independently of said braces for the purposes set forth. 60

In testimony whereof I set my hand, in the presence of two witnesses, this 20th day of December, 1897.

ROY BERKELEY SIMPSON.
